UNITED STATES PATENT OFFICE.

JACOB JACOBSEN, OF SAN FRANCISCO, CALIFORNIA.

VACUUM FEEDING DEVICE.

Application filed May 18, 1921. Serial No. 470,678.

To all whom it may concern:

Be it known that I, JACOB JACOBSEN, a citizen of the United States, residing at the city and county of San Francisco and State of California, have invented new and useful Improvements in Vacuum Feeding Devices, of which the following is a specification.

This invention relates to a vacuum fuel feeding device for internal combustion engines, and especially to a device of this character which is actuated by the suction produced in the intake manifold of the engine when in operation and which will elevate the gasoline from the main storage tank to an auxiliary tank from which the gasoline will flow by gravity to the bowl of a carburetor.

One of the objects of the present invention is to generally improve and simplify devices of this character, to provide an automatic valve mechanism, and to provide a float actuated lever mechanism of simple design for operating the valves.

Another object of the invention is to provide a novel cover structure, and means for securing the same without resorting to such devices as exterior bolts, screws, etc.

Further objects will hereinafter appear.

The invention consists of the parts and the construction, combination and arrangement of parts as hereinafter more fully described and claimed, having reference to the accompanying drawings, in which:

Fig. 1 is a central vertical section of the vacuum feeding device.

Fig. 2 is a section taken at right angles to Fig. 1.

Fig. 3 is a perspective view of the valve actuating lever.

Fig. 4 is an enlarged detail sectional view of the cover showing the securing tube, the venting valve and the suction valve.

Fig. 5 is a perspective view of the float actuated lever.

Referring to the drawings in detail, A indicates a cylindrical tank or container provided with a bottom section 2 and a fixed cover section 3, in which is formed an opening 4. Forming a closure for said opening is a removable cover 5, and dividing the interior of the tank A into two compartments, as shown at 6 and 7, is an intermediate bottom section or partition member 8. This member is horizontally disposed and has an opening formed therein as indicated at 9. The opening is cut or pressed out of the plate

8 and lugs are formed thereon as at 10 to form a support for a fibre washer 11, which serves as a bearing or guide for a stem 12 of a float 13. Also secured to the intermediate bottom section 8 is a cylindrical extension 14, and forming a closure therefor is a plug 15 in which is formed two inlet openings 16, a connecting passage 17, and a discharge passage 18. The openings 16 communicate with the interior of the cylindrical extension 14 and with the connecting passage 17, and the discharge opening 18 similarly communicates with the connecting passage. Forming a closure for the lower end of the extension 14 is a bottom section 19 through which the members 16 extend, and forming a normal closure for the discharge opening 18 is a disk valve 20 which serves the function of a check valve which will hereinafter be described.

Forming a part of the removable cover section 5 is a central section 21 which is cylindrical in shape. Forming a part of the member 21, or secured to the bottom portion thereof, is a pair of interspaced bearing brackets 22. Pivotaly mounted as at 23 between the upper ends of the bearing brackets is a lever 24, and pivotaly mounted as at 25 between the lower ends of the bearing brackets is a valve actuated lever 26 which is connected with the float 13 by means of a link or rod 27. The valve lever 24, as clearly illustrated in Fig. 3, is approximately bail shaped. The upper end of the lever terminates in a hook shaped projection 28, while the lower ends of the lever terminate in lugs 29 and 30. The lug 30 supports a venting valve generally indicated at 31, see Fig. 4, while the lug 29 supports a suction valve 32. The lever 26 consists of one arm, the forward end of which is bail-shaped as at 33 to form a pair of bearing extensions 34, receiving the pivot pin 25. The lower end of the bail terminates in a hook 35, and a coil spring 36 connects the levers 24 and 26 by being attached to the respective hook like extensions 28 and 35 as shown in Fig. 1. The lever arm 26 is further provided with a pair of stop members 36 and 37; the stop 36 controlling the lowermost position assumed by the float 13, and conversely the stop 37 the raised or uppermost position of the float.

Formed within the member 21 is a central chamber 38. Formed in the bottom of the chamber is an opening through which passes a tube 39, and also formed in the bottom section of the chamber 38 is an opening for

the reception of the venting valve 31. The upper end of the opening terminates in a valve seat 40 with which the valve is adapted to engage when assuming closed position. 5 Formed directly on one side of the central extension 21 of the cover is an angularly disposed boss 42. This boss is cored and tapped to receive a pipe 43, and the lower end of the cored opening terminates in a 10 valve seat 44 which cooperates with the suction valve 32, which will hereinafter be described.

The tube 43 is connected with the intake manifold of an internal combustion engine 15 not here shown. A second tube entering through the cover 5, and indicated at 45 is connected with the storage tank for the reception of gasoline or the like, and a third tube connected with the bottom section 2 as 20 at 46 delivers the gasoline by gravity to the bowl of a carburetor. The cover 5 as previously stated is removable. The tube 39 extending therethrough is turnably mounted in the bottom section of the extension 21, but 25 the lower end of the tube is threaded and is adapted to be received by a threaded boss 50 secured to the intermediate bottom section 8; the upper end of the tube being shouldered as at 51 to form a head like projection 30 which will exert a downward pull on the cover 5 when the tube is turned; the tube being furthermore slotted as at 52 to permit it to be turned by a screw driver or like device. The central chamber 38 formed in 35 the cover is normally closed by a plug 53. This plug is however provided with an air vent opening 54 to permit the chamber 38 to be in constant communication with the atmosphere.

40 In actual operation we will assume that gasoline as been previously admitted to the chamber 6, and that the lower chamber 7 has been completely filled. During the operation of the engine, it is obvious that the 45 gasoline admitted will gradually drain from the chambers 6 and 7 through the pipe 46 which is connected to the carburetor. The gasoline level in the upper chamber 6 finally becomes so low that the weight of the float 50 will trip the lever 26 and cause it to assume the position shown in Fig. 1. When this happens it can readily be seen that the spring 26^a exerts a pull on the valve lever 24 which will cause it to assume the position 55 shown in Fig. 1. This exerts a downward pull on the valves 31 and 32, causing the valve 31 to close with relation to its seat 40, and the suction valve 32 to open with relation to its seat 44. The pipe 43 is continu- 60 ously subjected to a considerable vacuum due to the fact that its opposite end is connected with the intake manifold of the engine. Air contained in the chamber 6 will thus be quickly removed and a sufficient 65 vacuum will be produced within the cham-

ber 6 to cause an inflow of gasoline from the storage tank through the pipe 45. The gasoline thus admitted will gradually fill the chamber 6 and the float will continue to rise until further movement is checked by 70 the stop member 37. The spring 26^a will simultaneously, or just previous to the engagement of the stop, pass beyond the center 23 and will thus trip the lever 24, causing it to open the venting valve 21 and simultaneously close the suction valve 32. Air is thus admitted and the vacuum broken and the gasoline will now drain freely into the lower chamber 7, that is it passes around 80 the guide washer 11 and downwardly through the cylindrical extension 14, from where it escapes through the member 16, the connecting passage 17, and the discharge opening 18; the hydrostatic pressure being sufficient to lift the check valve from its 85 seat, thus permitting the gasoline to enter the chamber. The float 13 will again gradually settle as the gasoline is drained or consumed by the carburetor, and it will again assume its lowermost position when 90 the spring 26^a passes the center of the pin 23, as the lever 24 will then trip and close the vent valve 21, and simultaneously open the suction valve 32; the extreme lowermost 95 position of the valve being limited and checked by the stop member 36. This lowermost position is assumed until the gasoline level is again raised to the point where the automatic tripping action takes place; the circle of operation being intermittently 100 repeated and repeated as long as the engine is in operation. In fact as far as the principle of operation is concerned, the present device is identical to the standard form of 105 vacuum feeding devices now in general use. The real novelty, as far as the present invention is concerned, is the general construction of the levers shown in Figs. 3 and 5; the construction of the removable cover 5; the method of securing the same by means 110 of the tube 39, and the general arrangement and construction of the cylindrical extension 14 and the check valve 20.

In operation it is obvious that it is not only necessary to vent and admit air to the chamber 6, but it is also necessary to vent the chamber 7. This is continuously vented in the present instance through the medium of the tube 39 as this tube is open and in constant communication with the atmosphere 115 through the chamber 38 and the vent passage 54. In fact this tube serves three functions, first that of a continuously open vent for the chamber 7; secondly that of a tie or stay rod for securing the removable cover 5; and third, that of a priming connection for partially filling the chambers 6 and 7, if they should be completely 120 drained; the priming being accomplished by merely removing the plug 53 and pouring 125 130

gasoline into the chamber or compartment 38. Gasoline poured into this chamber will drain through the tube 39 into the chamber 7 and it will thus supply a sufficient quantity of gas to start the engine and thereby create the suction required to operate the device.

A gasket may be interposed between the head 51 of the tube 39 and the bottom of the extension 21 to form an air-tight connection between the same. A gasket should similarly be interposed between the removable cover 5 and the seat formed for its reception. These are the only gaskets and tight joints required in the present instance. The entire mechanism is exceedingly simple and substantial in construction. The cover 5 can be quickly and readily removed or replaced by means of the rod 39; screws, bolts, etc., being entirely eliminated. The levers 24 and 26 are exceedingly simple in design and are in fact so constructed that they may be stamped and formed by a die operation. The float 13 must be inserted through the opening closed by the cover 5 when the mechanism as a whole is being assumed. Considerable trouble is often encountered in placing the stem 12 in its guide bearing, such trouble is however avoided in the present instance as the guide bearing or washer 11 is placed below the surface of the bottom 8. A recess is thus formed in the bottom which is easily located by the guide stem. Once the rod 12 has been located with relation to the recess, it is obvious that it is fairly easy to move the stem about until the guide bearing in the washer is located. The difficulty of entering the guide stem 12 is not so great when the apparatus is first assembled, for instance in a factory, as it may be placed in position before the cover 3 is secured; but it is obvious that considerable difficulty is encountered if the apparatus is taken apart later on as the float can only be inserted and removed through a small opening closed by the cover 5.

By referring to Fig. 2, it will be seen that lugs 42 and 42^a are formed on the cover and that these are disposed on an angle. This is of considerable importance as it permits the tubes 43 and 45 to be connected with the cover without employing elbows, nipples, etc.; that is tubes 43 and 45 are preferably constructed of copper or the like, and as such may be bent to form a goose-neck connection, thus avoiding the use of elbows, etc., particularly as they enter the cover on an angle. In fact all connections with the tank are made through the cover, thus materially simplifying the structure as a whole.

While certain features of the present invention are more or less specifically illustrated, I wish it understood that various changes in form and proportion may be resorted to within the scope of the appended

claims, similarly that the materials and finish of the several parts employed may be such as the experience and judgment of the manufacturer may dictate or varying uses may demand.

Having thus described my invention, what I claim and desire to secure by Letters Patent is—

1. A vacuum feeding device comprising a tank divided into an upper and a lower compartment, a removable cover member for the upper compartment, a rod extending therethrough, said rod having a central passage formed therein in communication with the atmosphere at one end and in communication with the lower chamber at the other end, means forming a connection between the upper end of the rod and the cover, and means for exerting a pull on the rod to secure the cover.

2. A vacuum feeding device comprising a tank divided into an upper and a lower compartment, a removable cover member for the upper compartment, a rod extending therethrough, said rod having a central passage formed therein in communication with the atmosphere at one end and in communication with the lower chamber at the other end, means forming a connection between the upper end of the rod and the cover, a threaded extension on the lower end of the rod, and a threaded member within the container for the reception of said threaded extension.

3. A vacuum fuel feeding device comprising a tank divided into an upper and a lower compartment, a top for the tank having an opening therein, a closure for the said opening, interspaced brackets within the upper compartment and a valve lever secured to the brackets, an actuating lever also carried by the brackets and connected at one end to the valve lever and at the other end to a float, the said brackets, levers and float depending from the closure.

4. A vacuum fuel feeding device comprising a tank divided into an upper and a lower compartment, a top for the tank having an opening therein, a closure for the opening comprising a plate having a cylindrical well therein closed by a plug, the said well having an opening therein forming a valve seat, a valve coacting with the seat and a valve lever carried by the closure for operating the same, the said well having constant communication with the atmosphere.

5. A vacuum feeding device comprising a tank divided into an upper and a lower compartment, a check valve connecting the same, permitting a flow of liquid from the upper compartment to the lower compartment, but checking movement in the opposite direction, a removable cover for the upper compartment, a central projection formed on the cover, a chamber formed therein, a head and tube extending through said chamber.

ber and the bottom thereof, a threaded boss placed within the tank, a threaded connection on the lower end of the tube adapted to be received by the threaded member, said 5 tube adapted to exert a downward pull on the cover to secure the same, and said tube forming a venting connection between the lower compartment and the atmosphere, a screw plug forming a closure for the chamber formed in the cover, and a venting passage in said plug and in constant communication with the atmosphere.

6. A vacuum fuel feeding device comprising a tank divided into an upper and a lower compartment, a removable top for the tank carrying interspaced brackets thereon, a substantially bail-shaped lever having a lip thereon secured within the brackets, a substantially bail-shaped actuating lever having 20 a lip thereon also secured within the bracket, a spring connecting between the lips on the levers, and stops on the actuating lever for limiting its motion.

7. A vacuum feeding device comprising a 25 tank, a partition member therein dividing the tank into an upper and a lower chamber, a check valve carried by said partition member permitting a flow of liquid from the upper chamber to the lower chamber, a removable cover for the upper chamber, a pair of bearing brackets secured to the cover, a valve lever pivotally mounted between the bearing brackets, a float actuated lever also pivotally mounted between the brackets, a 30 spring connecting the levers and exerting a pull between the same, a venting valve and a suction valve actuated by the valve lever and adapted to be alternately opened and closed thereby, a float connected with the 35 last named lever and adapted to impart movement thereto, a suction pipe communicating with the suction valve, a venting tube connecting the cover and the partition member and forming a constant vent for the 40 lower chamber, a liquid supply tube connected with the upper chamber, and means limiting the movement of the float actuated lever in either direction.

8. In a device of the character described 45 the combination with the tank and the partition member mounted therein, dividing the tank into an upper and a lower chamber, of a cylindrical extension secured to the partition member, a bottom for said cylindrical 50 extension forming a closure therefor, an opening formed in the partition member in communication with the upper end of the cylindrical extension, lugs formed around the edge of said opening and a guide washer 55 secured between said lugs.

9. In a device of the character described 60 the combination with a tank and the partition member mounted therein, dividing the tank into an upper and a lower chamber, of a cylindrical extension secured to the

partition member, a bottom for said cylindrical extension forming a closure therefor, an opening formed in the partition member in communication with the upper end of the cylindrical extension, lugs formed around the 70 edge of said opening, a guide washer secured between said lugs, a casing secured to the bottom of the cylindrical extension, a pair of upwardly extending extensions on said casing entering the bottom, a passage formed in each of said extensions, a connecting passage formed in the casing connecting said 75 passages, a discharge passage formed in the casing in communication with the connecting passage, a valve seat formed at the upper end of the discharge passage and a disk valve movable between said seat and the bottom of the cylindrical extension.

10. In a device of the character described the combination with the tank and the partition member secured therein dividing the tank into an upper and a lower chamber, of a cylindrical extension secured to the partition member and projecting downwardly into the lower chamber, a bottom member 80 for said cylindrical extension forming a closure therefor, an opening in the partition member communicating with the upper end of the cylindrical extension, a casing secured to the bottom of the cylindrical extension, said casing having a pair of upwardly extending extensions passing through the bottom of the cylindrical extension and secured thereto, a passage formed in each of 85 said extensions, a cross passage in the casing connecting said passages, a discharge 90 passage communicating with the cross passage and also formed in the casing, a valve seat formed at the upper end of said passage, and a valve disk movable between said 95 seat and the bottom of the cylindrical extension. 100

11. In a device of the character described the combination with the tank and the partition member mounted therein dividing the tank into an upper and a lower chamber, of a removable cover for the upper chamber, a tube extending through the cover, a threaded boss secured to the partition member, a threaded extension on the lower end of the tube adapted to be received by the threaded boss, and a head member on the upper end of the tube engaging the cover and permitting turning movement to be imparted to the tube, said tube forming a venting connection between the lower chamber and the atmosphere, and said head member on the tube exerting a downward pressure on the cover to secure the same. 110

12. A vacuum fuel feeding device comprising a tank, a top for the tank having an opening therein, a closure for said opening, interspaced brackets carried by the closure and supporting a valve lever thereon, an actuating lever also carried by the brackets and 120 130

connected at one end to the valve lever and at the other end to a float, the said brackets, levers and float depending from the closure being removable through the opening in the 5 top of the tank as the closure is removed.

13. A vacuum fuel feeding device comprising a tank, divided into an upper and lower compartment and having an opening

therein, a closure for the opening having a well therein, a hollow tube carried by the 10 closure and extending into the well, the said hollow tube providing means for fastening the closure, venting the tank and priming the same when the fuel tank has been exhausted.

JACOB JACOBSEN.
